US0D1059131S

(12) **United States Design Patent** (10) Patent No.: **US D1,059,131 S**
(45) Date of Patent: ** Jan. 28, 2025

(54) **VACUUM BOTTLE**

(71) Applicant: **ZOJIRUSHI CORPORATION**, Osaka (JP)

(72) Inventors: **Yuki Ikeda**, Osaka (JP); **Teruhisa Toyoda**, Osaka (JP)

(73) Assignee: **ZOJIRUSHI CORPORATION**, Osaka (JP)

(**) Term: **15 Years**

(21) Appl. No.: **29/806,781**

(22) Filed: **Sep. 7, 2021**

Related U.S. Application Data

(62) Division of application No. 35/510,074, filed on Feb. 5, 2020 (U.S. filing date under 35 U.S.C. 384), and having an international filing date of Feb. 5, 2020, now Pat. No. Des. 942,201.

(51) **LOC (15) Cl.** **07-10**

(52) **U.S. Cl.**

USPC **D7/608**

(58) **Field of Classification Search**
